CIRCULAR MACHINE FOR KNITTING RING-
LESS HOSIERY

Gaither McKinley Jones, Burlington, N. C., assignor to May Hosiery Mills, Inc., Burlington, N. C., a corporation of North Carolina

Application March 21, 1935, Serial No. 12,309

8 Claims. (Cl. 66—8)

This invention relates to circular hosiery knitting machines. It has for its object the accomplishment of that which has already been done in full fashion knitting machines, namely, the avoidance of rings or shadows in the fabric of the knitted stocking.

It is of course known that the cause of the above defects originates in the taking of the yarn from a single cone or spool, in which it frequently happens that a number of yards may be defective as to color, luster or gage, which defective portion when knit into the hose in consecutive courses produces bands contrasting with the adjacent fabric.

15 This may be avoided by drawing the yarn simultaneously from a plurality of cones, and knitting it into consecutive courses, for by the law of chance, it is not likely that defective places will be encountered at the same time in the three cones, and consequently, courses knit from the defective cone will be alternated with courses of perfect yarn from the other cones and the rings or shadows will not appear.

The problem of taking yarns from several sources was not particularly difficult of solution in its application to full fashion machinery, for the transfer from one cone to another can readily be made by suitable carriers moved into and out of operation at the ends of the blank, but 25 the adaptation of circular knitting machines to this principle of operation has necessitated ingenious additions and re-organization which constitute the subject of this application.

One of the objects of the present invention is 35 to provide additional feeds and corresponding additional stitch and leveling cams disposed at suitable arcuate intervals about the needle drum for drawing yarns from the additional cones and incorporating them simultaneously into the 40 knitted fabric in successive courses.

Another object of the invention is to provide 45 means for rendering the said additional feeds and cams inoperative at will, restoring the machine to its original function of knitting from a single cone only.

One of the objects of the invention therefore is the provision of auxiliary splice feeds, associated with additional stitching stations.

50 Other objects of the invention will appear as the following description of a preferred and practical embodiment thereof proceeds.

In the drawings which accompany and form a part of the following specification and through- 55 out the several figures of which the same charac-

ters of reference have been employed to designate identical parts:

Figure 1 is a side elevation of a circular knitting machine of the Scott-Williams type embodying the features of the present invention; 5

Figure 2 is a top plan view;

Figure 3 is a cross section taken along the line 3—3 of Figure 1;

Figure 4 is a vertical section through a portion of the machine showing the operating mechanism for one of the auxiliary splice feeds taken at such an angle that the path of reciprocation of the yarn feeds appears in front of the dial; 10

Figure 5 is a section taken along the line 5—5 of Figure 4;

Figure 6 is a vertical section illustrating the correlated means for simultaneously rendering the auxiliary leveling cams and sinker cams active or inoperative;

Figure 7 is a bottom plan view of the sinker 20 cam track;

Figure 8 is a plan view illustrating the means for holding down the knitted hose at the end of the adjacent auxiliary stitching stations;

Figure 9 is a perspective in detail of one of the 25 depressing means;

Figure 10 is a diagrammatic view of the four cams instrumental in the effecting of the operation of the auxiliary devices of the present invention; and 30

Figure 11 is a development of the needle contour illustrating the position of the additional stitching and leveling cams.

Referring now in detail to the several figures, the numeral 1 represents a hollow tubular standard supporting at its top the needle drum 2 and at its sides, the cam shafts 3 and 4, which carry the cams through which the functions of the machine are performed, said shafts 3 and 4 being synchronously driven by suitable means 40 which it is not considered necessary herein to illustrate and describe.

The needle drum 2 is of conventional construction being best shown in Figure 6 comprising a hollow cylinder having the exterior surface 45 deeply grooved longitudinally as at 5 for the reception of the needles 6, the latter being slideable in said grooves with a frictional fit. The needles as is customary in the art, are held in place by resilient bands 7. The lower ends of the 50 needles are provided with outwardly extending butts 8 which in the normal machine as heretofore constructed are engaged on their lower edges by a cam 9 for elevating the needles, the stitching cams 11 and 11' and the central cams

10 and 10' for switching the needles to produce the stitching slope of the needle contour in either direction of oscillation of the cylinder. The cam 31 raises the needles to normal elevation after 5 the stitch is made in the reverse oscillation of the cylinder.

The knitting machine is provided with normal feeds, see Figure 2, including a feed 12 for yarn derived from the cone 13 from which the basic 10 fabric of the stocking is knit, and the intermittently operated splice yarn feeds 97 incorporate splice yarn into the spliced portions of the stockings.

The drum 2 is provided with inner and outer 15 sinker rings 16 and 17 provided with aligning radial grooves which grooves are staggered with respect to the needle grooves in the cylinder. Sinkers 18 slide in said grooves, between the needles. Each sinker is provided with an off-set 19 20 lying in an endless cam track 20, see Figures 4 and 7. By means of said cam track the sinkers are slidably reciprocated radially with respect to the needle drum 2 and intersect the circular bank of needles. Each sinker is provided with a 25 nose 21 adapted to engage the yarn at the side of a needle and thus perform its part in the loop forming operation. The needle drum 2 is revolvable in either direction and the needles are operated by the cams in customary manner so that 30 the hooked ends of the needles intersect the zone of the sinker nose 21 in each direction of movement of the needle. Upon upward movement of the needle the loop surrounding the needle descends below the latch 22 and on the reverse 35 movement of the needle the latch is closed by the loop and the latter is shed, the sinker drawing the yarn across the plane of two adjacent needles, forming a new loop.

In the ordinary operation of a knitting machine 40 of this type, the cylinder rotates continuously. When the portion of the stocking to be spliced is reached, a splice thread is presented to the needles by the splice feed which reciprocates so as to make the presentation of the splice yarn to 45 the needles intermittent so that the splicing takes place during only a part revolution of the knitter. The stocking as knit descends through the tubular middle portion 23 of the needle drum, the latter having a spiral feather 24 which in the 50 rotation of the drum propels the finished portion of the stocking downward. The stocking when completed is removed through a hand hole 25 in the standard 1. In the knitting machine as illustrated, a dial 26 is formed in the hinged top 27 55 of the knitting machine, said dial being in juxtaposition to the needles for forming the welts of the stockings in known manner. The top may be swung open giving access to the working ends of the needles and to the knitting. The top affords the support for certain fulcra and other appurtenant mechanism.

The present invention proposes to add to the conventional circular knitting machine as at present known and above described, two additional 65 stitch forming stations in addition to the single station inherent in the original machine, drawing yarn from two additional spools or cones. In the development of the needle contour shown in Figure 11, these new stations are represented 70 by reference characters 28 and 29 and since that part of the bank of needles represented by the level stretch 30 and 31 in Figure 11 is concerned with transfer mechanism carried in the dial and cannot be disturbed, the additional stations 28 75 and 29 must be crowded into a space scarcely

more than half the circumference of the needle bank.

For the purpose of forming loops or stitches at the additional points indicated, it is necessary to form two distinct needle peaks 32 and 33, the 5 rising slopes being produced by the leveling cams 34 and 36 while the declining slopes are produced by the stitch forming cams 36 and 37, the lower surfaces of the butts of the needles riding upon the top faces of the leveling cams and the upper 10 surfaces of said needles riding against the lower faces of said stitch forming cams as the needle drum revolves. In addition to providing the needle peaks at the desired knitting stations it is of course essential to provide for corresponding 15 knitting movements of the sinkers at the additional stitch forming stations and also to provide feeds both normal and splicing feeds at each of said stations.

The stitching and leveling cams will now be 20 described. Figure 3 shows that the leveling cams 34 and 35 are pivotally mounted as at 38 and 39 to the stationary base or standard, so that these cams can be swung into or out of the paths of the butts of the needles. The leveling cam 34 is 25 connected by a link 40 to a vertical rod 41, see Figure 1, the lower end of which is in operative relation to the cam 42 shown in Figure 10. Said cam is mounted on the cam shaft 3 and rotates synchronously with the other cams on said cam 30 shaft as will appear. When the rod 41 is on a cam elevation, the cam 34 is pulled out of the path of the needle butts. When the rod 41 is in a depression on the cam 42 the cam 34 is swung to a position in which it is in the path of the 35 needle butts. Since one-half of the circumferential bank of needles have shorter butts than the other half as will appear from an inspection of Figure 3, it is obvious that when the cam 34 is 40 swung into operative position it contacts the shorter butts and thus rides under the longer butts until the sufficient number of needles having the longer butts has been elevated by said cam to provide a space into which it slips against the wall of the needle drum and therefore in the 45 path of the needles having the shorter butts.

The leveling cam 35 is quite similar to the leveling cam 34 being connected to a link 43 which in turn is connected with a rod 44 contacting the cam 45 on the cam shaft 3 and being operated 50 thereby.

The stitch forming cams 36 and 37 are formed at the inner ends of slides 46 and 47 which operate in guiding frames 48 and 49 suitably positioned with respect to the needle drum. The 55 slide 46 is provided near its outer end with a roller or similar device 50, and the frame 48 is provided with a bridge piece 51 between which and said roller, the nose of a sliding cam 52 extends. When said nose is moved to the right it wedges 60 between the bridge piece 51 and the roller 50, drawing the slide back and causing the cam to recede from the path of the needle butts. The cam 52 is at the forward end of a link 53, the rear end of which is connected to a rocking lever 65 54 fulcrumed about a vertical post 55 and extending to the opposite side of the machine where it is connected to a push rod 56 engaging the surface of a rotatable cam 57 on the shaft 4.

The stitching cam 37 is likewise formed with 70 a slide 47 operating in a fixed frame 49. In this instance, a roller 58 is provided and a bridge piece 59, but the roller is adjacent the needle drum while the bridge piece is remote therefrom. A link 60 having a wedge-like cam 61 is provided, 75

the cam lying between the roller and bridge piece and when the link 60 is pulled, pushes the roller and with it the cam 37 into the path of the needles. Reverse movement of course withdraws the cam 37 from the path of the needles. The link 60 is connected to a bell crank 62 having a fixed fulcrum, the opposite limb of said bell crank being connected by a link 63 to a push rod 64 having at its lower end a foot 65 engaging the 10 periphery of a rotary cam 66.

The stitching cams are operatively connected to the sinker retracting mechanism which will now be described.

Referring to Figure 4, it will be observed that 15 the sinkers are held normally pressed radially inward by a garter spring 67 in the normal machine in which there is only one stitching station. The sinkers are retracted at the proper point by a fixed cam 68, see Figure 7, projecting 20 out into the sinker cam track 20. In the present invention, since the sinkers must be reciprocated in forming the stitches at the two auxiliary stitching stations, two additional sinker cams 69 and 70 are provided, but on account of the fact 25 that these must be drawn out of operative position synchronously with the withdrawing of the stitching and leveling cams, they are made movable radially in or out with respect to the needle drum.

Figure 6 shows that the sinker cam 69 is in connection by means of a vertical web 71 with a slide 72 mounted in a hollow guide member 73 and that the slide when pulled radially outwardly draws the sinkers back with which it is at 30 the time in engagement. The sinkers thus become inoperative and no loop can be formed. The movement of each of the stitching cams for example, the cam 37, is synchronized with the movement of the sinker cam, for example, the sinker cam 69 by means of a rocking lever 74 fulcrumed at an intermediate point 75 to a fixed lug 76. The lower end of the rocking lever 74 has an off-set portion 77 engaging the inner face of the roller 58 while the upper end of said lever engages in a notch 78 in the slide 72. A thumb 35 screw 79 projecting into said slot makes it possible to adjust the relation of the sinker cam 69 to the stitching cam 37. A concealed spring 80 presses a plunger 81 outwardly against an over-turned flange 82 on the slide 72 of the stitching cam 37 and holds it normally in inactive position. The garter spring 67 normally holds the slide 72 in inoperative position. The lever 74 is normally held inert between the tension of 40 these two springs. When the stitching cam 37 is moved into operative position by the wedge cam 61 which acts between the bridge piece 59 and the roller 58, the lever 74 is rocked in a counter-clockwise direction as viewed in Figure 45 6, so as to bring the stitching cam 37 and the sinker cam 69 into operative position at the same time.

The connection between the stitching cam 36 and the corresponding sinker track cam 68 is substantially identical to the arrangement just described.

The cams 42 and 66 which control the leveling cams are so set on the shaft 3 with respect to the cams 45 and 57 which control the stitch forming cams that the stitch forming cams, leveling cams and the sinker track cams of the auxiliary knitting stations all move into and out of operative position simultaneously.

The auxiliary feeds which correspond to the additional stitch forming stations are illustrated

in Figures 1, 2, 4 and 5. They comprise brackets 83 and 84 fixed with respect to a rocking lever 85, and adjustable with respect thereto by means of a screw and slot connection 86. The brackets are formed with over-turned ends 87 at the top 5 provided with a hole 88. A similar hole 89 is in the bottom of the brackets. Yarn from the two auxiliary spools or cones pass through the holes in the respective brackets. Rearwardly of the brackets the lever 85 is provided with upstanding posts 90 on each of which slides a block 91, against the resistance of a spring 92 surrounding said post and kept under normal tension between the block 91 and a nut 93. A pin 94 mounted in the lever 85 passes freely through 15 an aperture in the block and inhibits any tendency of the latter to rotate the post 90. The blocks extend laterally from behind the brackets, the extending portion of each block resting upon a lever 95, see Figure 4, pivoted to the lever 85. 20 The lever 95 has an extension 96 engaged by suitable operating means for rocking said lever in a vertical plane and raising or lowering the block 91. Said block carries a tubular guide 97 for receiving a splice yarn and bringing it into 25 operative proximity to the needles.

The means for reciprocating the block 91 for the purpose of bringing the splice feed 97 into and out of operative proximity to the needles comprises a push rod 98, the lower end 99 of 30 which slides in a guiding sleeve 100. The intermediate part of said push rod is formed as a sleeve 101, the axis of which is perpendicular to the adjacent portion of the push rod. Slidably mounted in said sleeve is a plunger 102 having a roller 103 at its inner end. Said plunger is normally maintained in retracted position by means of a spring 104 and the plunger may be pushed outwardly at the proper point in the cycle of operation of the machine by a rocking lever 105 pivoted at 106 to a fixed part of the machine 40 and having its lower end 107 in engagement with the cam flange 108 carried by a collar 109 which is reciprocated on the surface of the standard 1 by suitable means such as the pitman 110. Springs 111 and 112 normally respectively hold 45 the push rod 98 and the pitman 110 down.

The revolving needle drum is provided with means forming a ledge 113 on which the roller 103 may roll when in extended position. In front of the ledge 113 at a suitable point is the cam 50 114, see Figure 1. In that phase of functioning of the machine in which the spliced portions of the stocking are being knit, the roller 103 remains in retracted position, but rides intermittently upon the surface of the cam 114 once for 55 each rotation of the needle cylinder. This elevates the push rod 98 against the tension of the spring 111, raises the lever 95, lifts the block 91 and with it the splice feed 97, removing the splice yarn from operative relation to the bank 60 of needles. At the point in the knitting where it is proper to throw the splice feed out of action altogether, the pitman 110 lowers the collar 109, causing the lever 105 to swing inward against the pressure of the spring 104 urging the roller 103 outwardly so that when it rides upon the cam 114 it slides over upon the ledge 113 and stays there until by the rising of the collar 109, the lever 105 is permitted to swing outwardly at its upper end allowing the spring 104 to retract 70 the roller 103 pulling it back off of the ledge into its normal position. When the roller 103 is resting on the ledge 113, the splice feed 97 is maintained elevated and out of operative position. 75

This structure is substantially duplicated with respect to both of the auxiliary feeding stations.

Simultaneously with the withdrawal of the auxiliary stitching and leveling cams, and the 5 sinker track cams from operative position, both of the auxiliary feeds are elevated so as to throw them out of operation. This is accomplished by 10 rocking upwardly the lever 85 upon which the auxiliary feeds are mounted. Said rocking lever 15 is pivoted at the point 115 and the end of said lever remote from the auxiliary feeds is engaged by a push rod 116 operated synchronously with 20 said drum and simultaneously with the sinker path diverting means and the means which 25 forms the auxiliary stitching stations, so as to raise both the basic yarn and splice yarn feeds simultaneously with the obliteration of the auxiliary stitching stations. Said push rod is normally raised holding the lever 85 down to its normal 30 position in which the auxiliary feeds are in operative adjacency to the needles. When the push rod 116 recedes downwardly, the spring 117 lifts the lever 85.

Referring to the development of the needle contour shown in Figure 11, it is obvious that a depressor for the most recently knit courses is required at the points indicated at *a* and *b* so as to hold the stocking down and prevent it rising under the frictional contact with the needles 35 rising on the adjacent slopes. These depressors must be so constituted as to be withdrawn synchronously with the stitching and leveling cams and the sinker cams. With this end in view, the uprights 118 and 119 are provided, suitably secured by the screws 120 and 121, respectively, which hold the rollers 50 and 58 in place. Each 40 of the uprights is provided with an eye having a horizontal axis through which passes a sliding rod 122. The inner end of the rods 122 are freely connected to lugs 123 formed on the depressors 124 and 125. Said depressors are in the form of 45 rocking levers pivotally secured at the points 126 and 127 to the upper part of the revolving cylinder.

45 The depressor 128 illustrated in Figure 8 is the normal depressor associated with the sinker stitching station provided in the known type of machine and is not particularly concerned with the present improvements.

50 Since the rollers 50 and 58 move in and out as the stitching cams assume operative or inoperative position, the uprights 118 and 119 partake of the same motion. When they move out, the 55 depressors 124 and 125 are withdrawn. When they move in the depressors return to operative position. Springs 129 and 130 held in compression 60 on opposite sides of the eye at the top of each upright, perform the usual function of cushioning the movement of the parts which 65 they engage.

The operation of the circular type of knitting machine is well known and need not here be described in detail. It is understood that the shaft 3 rotates once in the making of a stocking being 70 geared to the needle drum so that the latter makes a single revolution for each course of knitting. Normally, during the knitting of a stocking on a machine embracing the improvements of the present invention, yarns are supplied to the 75 feeding means from as many as six different cones or a smaller number if desired, three of the yarns being designed for the basic fabric of the stocking while the other three are splice yarns. The several cams on the shaft 3 are so 80 relatively oriented that in the knitting of the leg 85

the splice feeds are maintained in inactive position, three yarns from three separate cones being employed at the three stitch forming stations in the simultaneous knitting of the three courses during a single revolution of the needle drum. 5 This continues until the portion to be spliced is reached, whereupon automatically one of several things may occur according to the setting of the pattern mechanism. If it be desired that the portion to be spliced, (the high splice, for example), shall consist of a yarn taken from a single cone, with a single splice thread, the auxiliary stitching and leveling cams and the corresponding sinker track cams move to inoperative position and said portion is knit with the 10 single basic yarn and splicing yarn as though the 15 improvements of the present invention were not present.

While I have in the above description disclosed 20 what I believe to be a preferred and practical embodiment of the invention, it will be understood to those skilled in the art that the details of construction as shown and described and, except as specifically claimed, are merely by way 25 of example and not to be construed as limiting the scope of the invention as claimed.

What I claim is:

1. Circular knitting machine for making ringless hosiery by simultaneously knitting successive courses from yarns derived from separate spools comprising in combination with the known needle drum, annular bank of needles and cooperating sinkers, the main stitching station and means for supplying a basic yarn and a splice yarn to said station; one or more auxiliary stitching stations, a basic yarn guide and a splice yarn guide for presenting a basic yarn and a splice yarn to each auxiliary station, a cam carried by said drum, individual means associated with each splice yarn guide, sequentially operated by said cam in the rotation of said drum, for reciprocating said splice yarn guides to and from operative position once during each rotation of said drum, and means for holding said splice yarn guides out of operation while permitting the basic yarns to be drawn from all stations, and means for withdrawing both said splice yarn-presenting means and basic yarn-presenting means for each auxiliary station out of operative position, and simultaneously obliterating said auxiliary stitching stations. 45

2. Circular knitting machine for making ringless hosiery by simultaneously knitting successive courses from yarns derived from separate spools comprising in combination with the known needle drum, annular bank of needles and cooperating sinkers, the main stitching station and means to supply a basic yarn and a splice yarn to said station; one or more auxiliary stitching stations, a basic yarn guide and splice 55 yarn guide for presenting a basic yarn and a splice yarn to each auxiliary station, a cam carried by said drum, individual means associated with each splice yarn guide sequentially operated by said cam in the rotation of said drum for reciprocating said splice yarn guides to and from operative position once during each rotation of said drum, and means on said drum for inhibiting the reciprocatory movement of said 60 splice yarn guides responsive to a cooperative position of said cam-operated means, and means synchronized with said drum to act after a determined number of rotations of said drum for shifting said cam-operated means in position 65 70 75 80 85 90 95 100

to be caught and retained by said inhibiting means.

3. Circular knitting machine for making ringless hosiery by simultaneously knitting successive courses from yarns derived from separate spools comprising in combination with the known needle drum, annular bank of needles and cooperating sinkers, the main stitching station, and means to supply a basic yarn and a splice yarn to said station, one or more auxiliary stitching stations, individual supports adjacent said auxiliary stations and normally stationary relative thereto, a basic yarn guide carried by each support and normally in operative position with respect to its station, a splice yarn guide on each support reciprocable with respect thereto and normally in operative position with respect to its station, means for reciprocating said splice yarn guides independently of said supports and sequentially to bring them into and out of operative relation to their respective stations in sequence once during each rotation of said drum, means for holding them out of operative position after a determined number of rotations of said drum, while permitting the basic yarn guide to remain in inoperative position, and means for simultaneously moving both supports together with the guides carried thereby out of operative position, and simultaneously obliterating said auxiliary stations.

4. Circular knitting machine for making ringless hosiery by simultaneously knitting successive courses from yarns derived from separate spools as claimed in claim 3, the means for reciprocating said splice yarn guides including a cam on said drum, push rods having a normal spring determined position, operatively connected to said guides, and members on said push rods successively displaced by said cam on each rotation of said drum.

5. Circular knitting machine for making ringless hosiery by simultaneously knitting successive courses from yarns derived from separate spools as claimed in claim 3, the means for holding each splice yarn guide out of position comprising a collar on said drum, a cam on the peripheral face of said collar, said collar forming a circumferential ledge adjacent the zone of said cam, a plunger carrying a cam displaced member, a spring normally retracting said plunger, means for pushing said plunger drumwards against the bias of said spring, normally overcome by said spring means for actuating said pushing means against the tension of said spring, movement of the plunger being thwarted by the peripheral face of said collar until said member engages said cam, being displaced by the latter to the level of said ledge, and shifted to said ledge by said pushing means.

6. Circular knitting machine for making ringless hosiery by simultaneously knitting successive courses from yarns derived from separate spools

as claimed in claim 3, the means for simultaneously moving both guides of both supports to inoperative position including a pivotal arm on which said supports are mounted, and means for rocking said arm, said rocking means being synchronized with said drum. 5

7. Circular knitting machine for making ringless hosiery by simultaneously knitting successive courses from yarns derived from separate spools as claimed in claim 3, the means for moving each splice yarn guide including a collar on said drum, a cam on the peripheral face of said collar, said collar forming a circumferential ledge adjacent the zone of said cam, a push rod having a normal spring-determined position operatively connected to said guide, a plunger, and a member on said plunger displaced by said cam on each rotation of said drum, the means for holding each splice yarn guide out of operative position comprising a spring normally retracting said plunger, means for pushing said plunger drumwards against the bias of said spring, normally overcome by said spring, means for actuating said pushing means, movement of the plunger being thwarted by the peripheral face of said collar 25 until said member engages said cam, being displaced by the latter to the level of said ledge, and shifted to said ledge by said pushing means, the means for simultaneously moving both guides of both supports to inoperative position including 30 a pivoted arm on which said supports are mounted, and means for rocking said arm, said rocking means being synchronized with said drum.

8. Circular knitting machine for making a ringless hosiery by simultaneously knitting successive courses from yarns derived from separate spools for the incorporation of additional splice yarns in certain areas, and selectively adapted to draw yarn at a single station if desired, comprising in combination with the known needle drum, 35 annular bank of needles and cooperating sinkers, the main stitching station, and means for supplying a basic yarn and a splice yarn to said station, means for creating and obliterating one or more auxiliary stitching stations comprising one 40 or more pairs of stitching and leveling cams movable into and out of operative relation to said needle bank, and means for diverting the track of sinkers in the region of the auxiliary stations into and out of operative relation to the needles, 45 means for synchronizing the movement of said sinker track diverting means and said cams so as to cause them to operate together, depressors at said auxiliary stations normally overlying the circumference of said needle bank at said stations, 50 and means for reciprocating said depressors into and out of obstructing position with the edge of the hose simultaneously with the obliteration of the auxiliary stitching stations, said means being directly connected to cams of the respective pairs 55 of stitching and leveling cams.

GAITHER MCKINLEY JONES.
